INSULATOR

John J. Taylor, Barberton, Ohio, assignor to The Ohio Brass Company, Mansfield, Ohio, a corporation of New Jersey

Application May 26, 1932. Serial No. 613,609

9 Claims. (Cl. 173—318)

This invention relates to electric insulators and especially to insulators which are subjected to high mechanical stresses and a wide range of temperature changes, and has for one of its objects the provision of an insulator which will withstand these conditions without injury to the dielectric material or other parts of the insulator.

A further object of the invention is to provide an insulator pin which will automatically compensate for differential expansion and contraction of the parts of the insulator so as to prevent undue strain upon the dielectric member.

A further object of the invention is to provide an insulator which shall be of improved construction and operation.

Other objects and advantages will appear from the following description.

The invention is exemplified by the combination and arrangement of parts shown in the accompanying drawing and described in the following specification, and it is more particularly pointed out in the appended claims.

In the drawing the figure is an elevation with parts in section showing one embodiment of the present invention.

The numeral 10 designates a dielectric member which may be made of porcelain or other suitable material. A metal cap 11 is secured to the dielectric member by cement 12 and the outer face of the insulator is preferably provided with a treated sanded surface at 13, as described in U. S. Patent #1,284,975, granted November 19, 1918 to A. O. Austin. The lower portion of the cap may be thickened, as shown at 14, and provided with an inclined face 15 to provide a firm support for the portion of the dielectric member subjected to the stress of a load and to prevent excessive stretching of the cap under the expansive force produced by the load on the insulator. The dielectric member 10 is provided with a recess having a coated sanded surface 16 and a pin 17 is secured in the recess by cement 18. The pin 17 is provided with one or more inclined bearing faces 19 and 20 which are approximately parallel to the bearing surface 15 and normal to the direction of the stress set up in the dielectric member by the load. The bearing faces 19 and 20 may be given a coating of wax, bitumen or other yielding material which will prevent the cement from adhering to the bearing surface and permit the surface to slide on the cement to compensate for differential expansion and contraction of the parts.

The cushion member 21 is placed above the upper end of the insulator pin to permit relative movement between the end of the pin and the inner end of the recess in the dielectric member. Below the bearing faces 19 and 20 the pin 17 is provided with resilient flanges 22 and 23. The entire surface of the pin exposed to the cement

is preferably coated with wax, bitumen or similar material to prevent the pin from adhering to the cement and to provide for movement between the pin and cement to compensate for load and temperature changes. When the pin is subjected to a heavy load, it has a tendency to exert a bursting stress on the dielectric member 10 and in order to prevent injury to the dielectric member, the cap is provided with a heavy band 14. With this arrangement the stress in the dielectric member is confined largely to compression to which the porcelain offers effective resistance.

If the cap 14 were made lighter so that it would expand, then the bursting stress would tend to expand the dielectric, placing the material under tension, in which the porcelain is relatively weak. The heavy band 14 thus makes it possible to support a heavy mechanical load. The band 14, however, contracts at low temperatures and produces a pinching stress on the enclosed dielectric member. This stress tends to break the upper portion of the dielectric member from the lower flanges but is overcome by the resistance produced by the pin. Ordinarily, the pin tends to contract at the same time that the cap contracts, which would tend to relieve the pressure exerted outwardly by the load, thus permitting the dielectric member to be compressed and broken by the contraction of the cap. This tendency is overcome by the fact that the wedging surfaces 19 and 20 move downwardly in their sockets when the pin 17 contracts and thus maintains an abutment for withstanding the inward pressure exerted by the cap 14. The resilient flanges 22 will yield vertically under the stress of the load to permit the pin to move downwardly and maintain a close fit between the cement and the wedging faces 19 and 20. When the temperature again rises so that pressure is relieved from the outside and the pin begins to expand, the resilient flanges 22 and 23 will assist the upward component on the pin exerted by the wedging faces 19 and 20 and thus restore the pin to its initial position. If the pin were not provided with means for returning it to its initial position and the friction of the surfaces 19 and 20 should prevent return movement, then the expansion of the pin under increased temperature at the same time that the cap 14 expands would produce a bursting force on the dielectric member not resisted by the expanded cap 14, tending to burst the dielectric. The resilient flanges 22 and 23 however insure a return of the pin to its original position, thus compensating for the expansion of the pin when the temperature rises.

The wedging surfaces 19 and 20 permit sufficient movement of the pin in the direction of its axis to compensate for unequal expansion and contraction of the metal and dielectric parts and

the flanges 22 and 23 assist in returning the pin to its uppermost position and prevent sticking of the parts, due to friction upon the surfaces 19 and 20, which heretofore has rendered compensating wedging surfaces unreliable and apt to produce fracture of the dielectric member by failure of the pin to return to its upper position after it has once been moved downwardly.

In the embodiment shown in the drawing, the bearing surface 19 adjacent the end of the pin is of slightly less diameter than the bearing surface 20 so as to effect a graded distribution of stress between the pin and dielectric member and so as to minimize any tendency for radial expansion of the pin to crack the dielectric adjacent the upper end of the recess in the dielectric member. This, however, is not an essential feature of the invention. The inner surface of the cap 11 is also coated with yielding material such as wax or bitumen to prevent the cement from adhering to the surface of the cap and to permit the conical surface 15 to slide upon the cement to compensate for unequal expansion or contraction of the parts. Usually it is not necessary to provide resilient means for restoring the cap after a wedging action. The bearing surface of the cap is much larger than that of the pin so that the pressure per unit area is much smaller on the cap.

In addition to providing resilient means for restoring the pin after longitudinal movement thereof, the flanges 22 and 23 being larger than the stepped portions 19 and 20 assist in centering the pin when the parts are assembled.

35 I claim:

1. An insulator comprising a dielectric member having a projecting portion, a cap secured to the outside of said portion, a pin extending into a recess within said portion, a cement filler surrounding said pin in said recess, said pin having a solid, conical, bearing member at the upper end thereof providing a rigid wedging bearing face engaging said filler, the angle of said bearing face relative to the direction of the load on said insulator being steeper than the critical angle at which said face will slip on said filler under said load and a resilient flange on said pin below said bearing face and extending radially into said filler and tending to restore said pin to a predetermined position after movement thereof under the force of the load on the insulator.

2. An insulator comprising a dielectric member having a recess therein, a cap secured to said member and a pin disposed in said recess, said pin having a solid, conical bearing member at the upper end thereof providing a rigid, conical, bearing surface for transmitting the load thereon to said dielectric member, and a resilient flange secured to said pin below said bearing surface and tending to restore said pin to its initial position after longitudinal movement thereof in the direction of the load on said insulator.

3. An insulator comprising a dielectric member, a cap surrounding a portion of said dielectric member, a pin disposed in a recess in said dielectric member in registration with said cap, yielding means interposed between the end of said pin and the inner wall of said recess, a solid, conical bearing member on the upper end of said pin having a rigid conical bearing surface, cement disposed in said recess and providing a bearing surface cooperating with the bearing surface of said pin, means for preventing said cement from adhering to the bearing surface on said pin, and a

resilient flange formed on said pin below said bearing surface and extending into said cement and tending to restore said pin after movement thereof in the direction of its axis to tighten said bearing surface in said cement.

4. An insulator pin having a rigid conical bearing surface, and a radially extending resilient flange.

5. An insulator comprising a dielectric member having a recess therein, a pin having one end thereof extending into said recess, cement for securing said pin in said recess, said pin having a rigid conical bearing surface at the inner end thereof, said surface being flared outwardly toward the end of said pin disposed in said recess, means for preventing said cement from adhering to said bearing surface, and a radially extending resilient flange on said pin engaging said cement and tending to restore said pin after movement thereof in the direction of its axis relative to said cement.

6. An insulator comprising a dielectric member having a recess therein, a pin disposed in said recess and having a plurality of rigid conical bearing surfaces flared outwardly toward the inner end of said pin, one of said surfaces being disposed at the inner end of the pin, means for preventing the cement from adhering to said bearing surfaces, and a radially extending resilient flange on said pin engaging the cement to restore said pin after movement thereof under the force in the direction of the load on said insulator.

7. An insulator comprising a dielectric member and a metal fitting member, said metal member having a rigid wedging surface for transmitting the load to said dielectric member, cement bonded to said dielectric member and formed to provide a wedging surface conforming to and cooperating with the wedging surface of said metal member but unbonded thereto, and resilient means secured to said metal member and engaging said cement and tending to hold said members in a predetermined position relative to each other and to restore said members to said position after relative movement thereof.

8. An insulator comprising a dielectric member and a metal member secured thereto, one of said members being disposed within a recess in the other, said metal member being provided with a rigid, wedging face for transmitting the load on said insulator, cement bonded to said dielectric member and formed to provide a wedging surface cooperating with and conforming to the wedging face of said metal member but unbonded thereto, and resilient means on said metal member engaging said cement for restoring said members after relative movement thereof under the force of the load on said insulator.

9. An insulator comprising a dielectric member, a cap surrounding a portion of said dielectric member, a pin disposed in a recess in said dielectric member and registering with said cap, a conical bearing member at the upper end of said pin having a rigid, conical bearing surface, cement disposed in said recess about said pin and conforming to and cooperating with the bearing surface of said pin, means for preventing said cement from adhering to the surface of said pin, and resilient means on said pin engaging said cement for restoring said pin after movement thereof tending to tighten said conical bearing surface against said cement.

JOHN J. TAYLOR.
